UNITED STATES PATENT OFFICE.

JOHN REECE, OF BOSTON, MASSACHUSETTS.

BUTTON-HOLE SEWING-MACHINE.

SPECIFICATION forming part of Letters Patent No. 349,359, dated September 21, 1886.

Application filed May 19, 1884. Serial No. 132,029. (Model.)

To all whom it may concern:

Be it known that I, JOHN REECE, of Boston, county of Suffolk, State of Massachusetts, have invented an Improvement in Button-Hole Sewing-Machines, of which the following description, in connection with the accompanying drawings, is a specification, like letters on the drawings representing like parts.

This invention is an improvement on the machine represented in United States Patent No. 240,546, granted to me April 26, 1881, to which reference may be had, and has for its object to simplify the construction of the stitching mechanism, whereby it is possible to make a firmer stitch with less strain upon the thread; also, to improve the button-hole-cutting mechanism, whereby the throw of the cutter may be adjusted to compensate for wear of the cutting-bed and always insure a clean cut; also, to improve the construction of the spreading device, whereby the button-hole may be better held in spread condition by the clamping mechanism; also, to improvements in mechanism for controlling the needle-thread, whereby the latter is slackened after the completion of the button-hole, and, as herein shown, the said thread-controlling mechanism is combined with and so as to be operated automatically by the mechanism which is employed to clamp the material in which the button-hole is being made; also, to improve the clamping mechanism which holds the material, and with the same there has been combined mechanism for automatically opening the clamp upon the completion of each button-hole.

The especial features in which my invention consists will be pointed out in the claims at the end of this specification.

Figure 1 is a side elevation, partially broken out, of a button-hole sewing-machine embodying my invention; Fig. 2, an under side view of the casing containing the feeding mechanism; Fig. 3, a top view of the mechanism represented in Fig. 2; Fig. 4, a section of Fig. 3 in the dotted line x x' ; Fig. 5, a sectional detail and partial plan of a part of the bed-plate to show some of the devices which enter into the mechanism which controls the automatic starting and stopping of the stitching mechanism; Fig. 6, a section of Fig. 5 in the dotted line x' x'' ; Figs. 7 and 8, sections of Fig. 6 on the dotted lines x^1 x^2 and x^3 x^4 ; Fig. 9, a

section of Fig. 5 on the dotted line x^1 ; Fig. 10, a section of Fig. 9 on the dotted line x^5 x^6 ; Fig. 11, a partial elevation of the left side of the machine to illustrate part of the thread-slacking mechanism and of the means employed to operate the devices (not shown) which clamp and unclamp the material being stitched; Fig. 11^a, a detail to be referred to. Fig. 11^b is a detail plan view of part of the devices shown in Fig. 11 for automatically unclamping the material when a button-hole is completed; Fig. 12, a detail showing part of the movable frame with the bed-plate and parts connected therewith to aid in starting and stopping the stitching mechanism; Fig. 13, a section of Fig. 12 on the dotted line x^5 x^6 , Fig. 12; Fig. 14, a broken partial plan of the bed-plate, showing one-half of the clamp which holds the material and part of the devices to operate the same. Fig. 14^a, a section of the rear end of finger 22 and under clamping member below it in the line y y of Fig. 14; Fig. 15, a section of Fig. 14 in the line x^7 x^8 , the clamping mechanism having been fully restored; Fig. 16, an elevation of the stitching-race for the under needle and the looper, and means to operate the said parts in the proper time as the race is partially rotated in one or the other direction, carrying with it the under needle and looper; Fig. 17, a view of Fig. 16, looking at it in the direction of the arrow 17^x; Fig. 18, a view of Fig. 16, looking at it in the direction of the arrow 18^x; Fig. 18^a, a rear elevation of the race and throat plate; Fig. 19 a top view of Fig. 16; Fig. 20, a detail of parts of Fig. 16; Fig. 21, a detail of devices for actuating the devices shown in Fig. 16; Fig. 22, a section of Fig. 21 on the line x^9 x^{10} ; Fig. 23, a broken detail and partial side elevation of the button-hole-cutting mechanism. Fig. 23^a is a detail plan view of the spreader; Fig. 24, a section of Fig. 23 in the dotted line x^9 x^{10} ; Figs. 25 and 26, sections on the line y of Fig. 22, the dotted line y^2 on the latter figure showing line of section for Fig. 21; Fig. 27, an edge elevation of the clutch mechanism; Fig. 28, a cross-section of the same, and Fig. 29 a section of the clutch mechanism in the line x^{10} x^{11} , Fig. 28.

In the machine herein described the movable overhanging frame a , the bed-plate a' , provided with the groove k' and fixed stud or pin

j^4 , the casing a^4 , the main shaft a^2 , its cam b , the strap c , needle-bar lever c' , block c^3 , needle-bar b' , needle d , the spring-arm w^7 , its adjusting-screw w^9 , the sectors e^2 , the rod e^4 to connect them, the partial gears d^2 and g^7 actuated by them, the disk f , the link f^2 , its attached eccentric f^3 , pins f^4 and f^5 , the connecting-link f^9 , the lever g , cam-disk j , provided with the grooves 6, 4, and 7, rock-shaft l , its lower arm, l' , its upper arm, l'' , and roller-studs l^1 , the under members, m , of the clamp and their serrated parts m^2 are substantially the same as in my said patent, wherein the same parts are designated by like letters.

15 It may be here stated that the general operation of my machine herein shown is the same as in the machine covered by my patent hereinbefore referred to, in that the material is held by a stationary clamp, and the stitch forming and cutting mechanisms are carried by a traveling frame, so that the button-hole is first cut in the material, the stitch-forming devices move along one side of the button-hole to work the same, then with a partial rotative movement around the eye, and finally back along the second side of the button-hole, to complete the same. The stitch-forming mechanism is at rest while the button-hole is being cut, and is automatically brought into operation when the traveling frame has retreated far enough to get the cutter out of the way of the needles, and when the button-hole is completed the operation of the stitch-forming mechanism is automatically suspended. The 35 longitudinal or traveling movements of the frame a , carrying the stitch-forming mechanism, are imparted to said frame from the groove 6 of the cam-wheel j , rotating on a hub attached to the stationary frame and acting on the stud j^1 , attached to the traveling frame, and the slight lateral movements of the said traveling frame are effected by the rock-shaft l , having arms l^2 and l' , engaging said cam and frame, respectively, all as in my patent afore-45 said.

50 The needle-bar b' in this instance has but one needle, (marked d), it having an eye and being supplied with thread d^2 from a suitable spool, S , the said thread being passed under the friction-plate d^4 , made adjustable as to its pressure by the nut d^5 , and thence under the slack-thread controller d^6 . The thread, after leaving the controller d^6 , is passed through a guide-eye in a vertical rod, d^7 , and then through 55 an eye in a spring-held lever, d^8 , an eye, d^9 , made in the upper end of the needle-bar, and the three eyes d^{10} d^{12} d^{13} , attached to the needle-bar.

60 The needle d at each descent is caused to penetrate the material at a little distance back from its edge, and when the needle arrives at the eye of the button-hole, the frame a , besides moving longitudinally, is moved laterally to cause the needle-bar and all the stitch-forming parts, to be described, both above and below the throat-plate to be partially rotated to carry the stitch around the said eye, the stitching

mechanism being so operated by means of the sector e^2 and gears d^2 and g^7 , the said sectors deriving their movement from the cam-groove 4 in the cam-wheel j , all as in my patent above referred to. The width of the stitching from the edge of the button-hole backward is controlled by the screw w^9 , passing through the lower end of the needle-bar and abutting 75 against the spring-needle carrying-arm w^7 , as in my former patent.

70 The overhanging movable frame a is moved both longitudinally and laterally, as in the patent referred to. The partial gear g^7 has a 80 depending bracket, 101, which receives and supports a horizontal stud, A , on which is pivoted the actuating-lever A' , which imparts motion to the looper 2, (see Figs. 1 and 18,) and under needle, 3, through suitable connecting devices, to be described. The lever A is shown as an elbow-lever, the lower arm of which is made ball-shaped (see Figs. 1 and 21) 85 to be engaged by the lever g , common to the said patent.

90 The lever g , joined at its rear end with the connecting-rod f^9 , extended upward through the center of the casing a^4 and cam-wheel j , has at its upper end a strap to embrace the eccentric projection f^3 , (see Figs. 21, 22, 25, 95 and 26,) forming part of the link f^2 . The link f^2 has at one side of it, near one end, a pin, f^4 , which enters loosely a hole in the disk f , (see Fig. 26,) and the eccentric projection f^3 is provided with a pin, f^5 , on which is placed a roller, f^7 , which latter enters a cam-groove, 46, (see Fig. 25,) in the stationary cam 45, (see Fig. 22,) secured by screw 47 in the bracket 43, rigidly attached to and movable with the frame a .

100 The lever A' has a pin or roller-stud, A^2 , which enters a cam-slot, A^{12} , in the looper-lever arm A^3 , attached rigidly by screw A^4 (see Fig. 16) to the looper-lever A^5 , having its fulcrum on the screw A^6 inserted in the 110 raceway-block A^7 , having its stem A^8 (see Fig. 1) rigidly fastened into the sleeve A^9 , fitted into the frame-work, the said sleeve at its lower end having fastened to it the partial gear g^7 .

115 The looper-lever A^5 (see Fig. 16) has mounted upon it loosely the looper-carrier A^{10} , the connection being by the screw A^{12} , (fully shown in Fig. 20,) the said carrier having at one side of it, at its outer end, preferably, a roller, 4, which, as the looper-lever A^5 is vibrated, bears against the cam-surface 5 (see Figs. 19 and 21) near the upper end of the lever A' . The roller 4 is maintained in contact with the said cam-surface 5 by one or more springs, two being 125 herein shown, (marked t and t' , see Fig. 19,) the said cam-surface and spring or springs serving to impart proper lateral movements to the looper, as will be hereinafter described, for the formation of the stitch.

130 The looper 2, (see Figs. 1 and 16,) connected with the carrier A^{10} by screw 10, has a point, 12, and a heel, 13, and at the rear of the said heel the said looper is bent at 14 to constitute

a throat, (see dotted lines, Fig. 19,) through which the under needle works, the heel 13 projecting into or toward the center of said throat, so as to spread the loop of the upper thread and leave a shoulder, behind which the under needle may ascend to enter the said loop.

The under needle raceway-block A⁷ (see Fig. 16) is grooved circularly for the reception of the under-needle block or carrier B, in which the under needle, 3, is held by suitable screws, 8, 9. The face of the raceway-block A⁷ is upwardly and backwardly inclined (see Fig. 18) with relation to the center line of the stem A⁸, in order that the under needle, 3, may pass diagonally upward and across the path of the vertically-movable eye-pointed needle d, and at the same time place itself in such relation to the said needle d and the looper 2, that the latter may pass into the space left between the upper and under needles near the eye of the former and the shank of the latter, as will be described. The raceway-block A⁷ is cut through at its rear side (see Fig. 18^a) to receive the sleeve B' (see Fig. 19) of the connecting-link B', the latter being joined with the block or carrier B, by means of the screw-pin B², the rear end of the said link being joined to the lever A' by the screw B¹. The upper end, 15, of the raceway-block A⁷ is provided with a vertical groove, 16, (see Fig. 18^a) to receive the dovetailed shank 17 of the throat-plate C, the said throat-plate being thus supported on the said block.

The depending portion 101 of what is called the partial gear g¹ (see Fig. 1) is provided with a thread-guide, 18, 19, and a suitable tension device, 20, to act upon the under thread. (Not shown.)

The upper serrated members, m', (see Fig. 1,) of the cloth or material holding clamps are pivoted at 21 (see Fig. 14^a) on the fingers 22, in turn pivoted at 23 (see Fig. 1) upon ears 24, rigidly secured to the lower members, m. The said fingers being normally kept elevated by springs 25, (see detail Fig. 14^a,) wherein the said finger, spring, and member m are shown in longitudinal section. Each finger 22 (see Figs. 1, 14, and 15,) is provided with an L-shaped link, 26, pivoted to it by a screw, 27, and extended through a slot in the lower clamp member, m, and below the latter the shoulders of the links are engaged by springs 28 (see Figs. 14 and 15) of the arms 29 of a rock-shaft, 30, journaled in bearings (see Fig. 1) attached to the under side of the bed-plate a'.

The arms 29 of the rock-shaft 30 are normally held up to relieve the fingers 22 from strain of the springs 28, by a spring, 31, (see Fig. 11;) and the outer free end of one of the said arms 29 is acted upon by the cam 32 of the cam-lever 33, pivoted at 34 on the bed-plate a', the said lever having at one side a pin, 35, against which acts a spring, 36, that normally turns the lever forward, as in dotted lines, Fig. 11. (See also Fig. 14.)

In Fig. 11 the handle 33 is shown in full lines as depressed or turned backward, its

cam 32 then acting upon the arm 29 to cause the springs 28 to pull down upon the connecting-links 26 and force the fingers 22 to and their clamping-surfaces m' m' against the material, to hold it to be cut and stitched. The cam-lever 33 is held locked in this position by a trigger-lever, D, (see Fig. 11,) pivoted at D' on a stud rising from the bed-plate, the front end of the said lever being acted upon by the spring-latch 37. (Shown in dotted lines, Fig. 11, and in full lines in the detail, Figs. 11^a and 14.) The spring-latch 37 has at its lower end a small projection, 102, adapted to catch under the front end of lever D when in the position shown in full lines in Fig. 11, so as to lift the said end of said lever when the lever 33 is turned from the position shown in full lines in Fig. 11 to the position 85 indicated by dotted lines in said figure, for a purpose which will be explained further on. The inner end of the lever D has pivoted upon it a trigger, D², provided with a slot to receive a pin, 38, which is made adjustable therein 90 and has depending from it a foot, 39. The pin 38 is acted upon by a lever, 41, having projecting from one side of it an incline, 40, the said lever having its fulcrum at 42 on the bracket 43 of the movable frame a. (See Figs. 95 11 and 11^b.) The pointed short arm of the trigger D² rests upon a ledge made at one end of the trigger-rest D³, attached by a screw to the bed-plate. (See Fig. 11.) In Fig. 11 the parts are in the position they will occupy 100 when the button-hole slit has been worked along one side and about the eye, the movable frame being about ready to be started forward to enable the last side of the button-hole to be stitched.

When the frame a was moved backward, or in the direction of the arrow 48, (Fig. 11,) the lower side of the incline 40 struck the pin 38 and the latter lifted the incline and the lever 41, carrying it, and this without at all disturbing the trigger; but as frame a starts forward or opposite the arrow 48, the forward or lower end of the incline 40 strikes under the pin 38, and by the time that the said pin reaches the highest part of the said incline, 115 the end of the button-hole having been reached, the pin 38 is sufficiently lifted to cause the pointed end of the trigger D² to be turned from above the ledge D³, thus permitting the rear end of the trigger-lever D to descend through 120 the action of the springs 28, before described. The pin 38 is adjusted in the slot of the trigger D², according to the length of the button-hole. As the trigger leaves the trigger-rest and the front end of the lever D ascends, it releases the latch 37 and permits the spring 36, acting upon the pin 35 of the said lever, to start the said lever, and the springs 28 complete the turning movement thereof into the dotted-line position, Fig. 11, in 130 which position the upper members of the clamp will be raised. Thus it will be understood that the unclamping of the material is accomplished automatically. As the material is un-

clamped to be removed the needle-thread must be slackened. This is accomplished automatically, as follows: The rear end of the trigger-lever D is joined by link E with the thread-slackening lever d^6 , pivoted at E^2 on a bracket, E³, having an attached spring, E⁴, which acts normally to keep the front end of lever d^6 elevated above the needle-thread between the tension device d^4 and the guide d^5 .

- 10 When the rear end of the lever D is released through the movement of the trigger, as stated, the lever 33, as before described, is started forward, and the latch 37, as it passes from under the lever D, lifts its front end, 15 draws down its rear end, and by the link E causes the thread-slackener d^6 to descend upon and pull the necessary amount of slack thread from the tension device d^4 , and as the latch 37 passes from the front end of the said lever D 20 the spring E⁴ is permitted to become effective to lift the thread-slackener lever and the rear end of lever D, thus leaving the slack thread free to be drawn out through the eye of the needle for the removal of the work.
- 25 The cam-wheel j has a projecting circular rim, 50, which is embraced by the jaws 51 of a dog, 49, herein shown as a curved bar, in order to pass the center of the cam-wheel. The end of the dog, which is provided with the jaws 51, 30 is acted upon by a spring, 52, which throws that end of the dog forward on the rim 50 whenever the other end of the said dog is acted upon by the lower arm, 53, of a three-armed lever, F, having its fulcrum on a stationary sleeve, t¹, (see Fig. 5,) projecting from the movable frame a. The upper arm, 54, of the lever F is moved in one direction by the eccentric 55, (see dotted lines, Fig. 1,) attached to the belt-pulley, and in the opposite direction through the spring 52, the belt-pulley being loose on shaft a².

When the cam-wheel is to be turned forward, or in the direction of the arrow thereon, Fig. 3, the arm 53 of the lever F will be thrown by the eccentric 55 against the end of the dog 49, causing it to turn, so as first to bite the rim 50, and then to carry the cam-wheel with it, the extent of movement of the cam-wheel depending upon the extent of the movement 45 of the arm 54 of the lever F toward the eccentric 55, such extent of movement being regulated by the feed-regulating device 56, (shown as a screw, made adjustable in one of the arms of the said lever F.)

- 50 The hub of the cam-wheel j (see Figs. 3 and 23) has a cam-projection, 57, substantially the same as the cam x in the patent referred to. The cam 57 acts upon a toe-piece, 58, adjustably secured in a groove in the rear end of the 55 cutter-lever G, having its fulcrum at G¹, and provided at its outer end with a cutter, G², of usual construction, the latter being adapted to descend upon the material resting upon the cutter-block G³, attached to a projecting portion, G⁴, of the casing a⁴, secured to the movable frame a.

To compensate for wear of the cutting-block

G³ and insure a clean cut, the beveled end of the toe-piece 58 (see Fig. 23) is acted upon by an incline of a sliding bar, 59, having an attached screw-threaded rod, 60, provided with a thumb-nut, 61, by which to actuate the said slide and regulate the movement of the cutting-lever and make its pressure on the block G³ more or less. The toe 58 of the cutter-lever G is kept in contact with the cam-projection 57 by means of the spring G⁵, acted upon at its free end by the screw G⁶ in the frame a.

The under members, m, of the clamp, pivoted each as at 62, (see Fig. 14,) are drawn together 80 at their inner ends by a spring, 63, attached to pins 64 of the said members. Each member m, near its inner end, at its under side, is provided with a roller-stud, 65, and the studs by the spring 63 are held against the outer 85 sides of the spreader n, (see Figs. 21, 22, 23, and 23^a), pivoted at n¹ on the casing a⁴. When the material is first clamped and the movable frame a is in its forward position the studs 65 rest against the sides of the spreader n, back 90 of the inclines or shoulders n², where the said spreader is narrowest, and as soon as the material has been clamped and cut, the inclines n², in the backward movement of the frame a, act upon and separate the roller-studs, thus 95 separating the members m, spreading the button-hole slit just prior to the penetration of the material by the needle d for the formation of the first stitch taken in the button-hole, the said roller-studs remaining in contact with 100 the wide part of the spreader until the button-hole has been stitched all around, the wide part of the spreader being a little longer than the longest button-hole to be stitched.

In the stitching of a button-hole, when the 105 needle arrives at the eye the lateral movement of the frame a is commenced by the cam-groove 7 and arms l¹ and l², as in my said Patent No. 240,546, and if the spreader-n were rigidly fixed to the movable frame it is obvious that the spreader, acting upon the roller-studs, would throw the clamp to one side, which would make it impossible to stitch a round or oval eye; and to obviate this difficulty and prevent the spreader from counter- 110 acting the effect desired to accomplish by the cam-groove 7, which is shaped to give the proper vibrations for the stitching of the eye, the said spreader has been pivoted so as to turn upon its pivot as the frame a is vibrated. 115

To automatically stop the feed movement or the throw of the dog 49 while the operator is placing the material in the clamp to be cut, the bed-plate is provided with a feed-arresting bar, o, (see Fig. 11,) placed in a groove at 125 its under side, and held therein by the heads of two screws, o¹ o², one at each side of the bar, near its ends, that one of the screws marked o² being shown in dotted lines. This bar is provided with an adjustable stop, o³, having 130 a depending lug, which is in the line of movement of the dog 49 as it is vibrated by the lever F. When the frame a is being moved forward to place the clamp in position to supply

it with the material to be stitched, the lever 33 is forward, as in dotted lines, Fig. 11, and when in such position the front wall of the recess 66 in the cam 32 is sufficiently far rearward to engage at the proper moment the front end of the feed-arresting bar *o*, which is in line with the said wall or the thick part of the cam, said bar being adapted to have a limited longitudinal or sliding movement in a slot in the stationary bed-plate *a'*. As the frame *a* travels forward the dog 49 in its vibrations strikes the projection *o*² on the bar *o*, thus gradually carrying the said bar forward until its front end comes in contact with the rear wall of the recess 66 in the cam 32, when the said projection *o*² will prevent the retraction of the dog 49 by the spring 52, thereby arresting the vibrations of said dog and the rotation of the cam-wheel *j*, and thus stopping the forward movements of the frame *a*, which carries the stitch-forming and cutting mechanisms.

The turning of the lever 33 into its full-line position, Fig. 11, to clamp the material preparatory to cutting the same removes the thick part of the cam 32 from the end of the feed-arresting bar, and the latter, being released, permits the dog 49 to be again moved to commence the rotation of the cam *j* and the forward movement of the frame *a*, the front end of the feed-arresting bar then freely entering the recess or chamber 66 in the lower end of the lever 33, so that the said bar is far enough forward to permit the dog 49 to be retracted by its spring 52, and thus the movements of the said dog and of the parts operated thereby are resumed.

The operations of the stitch-forming devices are suspended when the button-hole is being cut, and shortly before and afterward, during a part of the time when the cutter is moving forward to the cutting position and is retreating therefrom, as in the machine shown by my prior patent; and in order to stop or start the said stitch-forming devices automatically the bed-plate is provided with a controlling-bar, *p*, (see Figs. 1, 5, 6, and 12,) having at its under side, near its rear end, a recess to receive loosely a washer, *p'*, (see Fig. 8,) which latter rests upon the bed-plate and receives through it a bolt, *p*², upon which, above the bed-plate and controlling-bar, is placed a nut, *p*³, the construction and combination being such as to permit the front end of the controlling-bar to vibrate horizontally about the said bolt as a fulcrum and yet restrain it from longitudinal movement without first loosening the said nut, the said bar being moved from time to time to alter the length of the button-hole. This controlling-bar *p* is grooved at top along its inner edge (see Fig. 7) to receive an adjustable slide-bar, 67, (see Figs. 5, 6, and 12,) attached thereto by a screw, 69, the front end of the said slide-bar being beveled or inclined at 103 to permit the toe of arm 70, (see Fig. 6,) connected with the rock-shaft 71, to pass readily from the lower plane of the controlling-bar *p* to the top of the slide-bar 67 at a higher plane,

the top of the said slide-bar 67 being in the same plane as the high part or edge 68 of the controlling-bar *p*, so that the said toe may ride 70 upon the slide-bar while the frame *a* is being moved backward and while the first half or side of the button-hole slit is being stitched.

The frame *a* is vibrated or moved laterally by means of the cam *j*, the rock-shaft *l*, and its arms, as in the machine shown by my former patent, as the needle reaches the eye of the slit, and the outer end of the controlling-bar is swung laterally by a spring, 72, which rests against its outer side, the said spring being herein shown as composed of wire and held by a screw, 73. (See Fig. 5.) The side of the controlling-bar next the movable frame *a*, when the first half of the button-hole is being stitched, rests against and is held out by 85 means of a vibrator, *r*, made as a slide-bar, (see Figs. 12 and 13,) the said vibrator being guided in the movable frame and having a projecting arm, *r*², which rests against the rod *e*¹, which connects the upper and lower sectors, *e*². As the frame commences to vibrate to enable the needle *d* to penetrate the material about the eye, the rod *e*¹ is carried away from the arm 70, and the controlling-bar, acted upon by the spring 72, is made to move the 95 slide *r*, so that it follows the rod *e*¹ and gradually brings the high part 68 or outer portion of the controlling-bar under the toe of the arm 70, where it rests while the other half of the button-hole is being stitched, the said toe 100 dropping therefrom upon the lower plane of the said controlling-bar as the last half of the button-hole is finished. The rock-shaft 71 is provided with a second arm, 74, shown in Figs. 5 and 1.

The upper end of arm 74 is provided with a dog, 75, which projects therefrom sufficiently to enter the groove 77 (see Figs. 27, 28, and 29) in the clutch-wheel *M*, secured to the main shaft *a*² by the set-screw 78, whenever the toe 110 of the arm 70 is on the lower plane of the controlling-bar *p*, the dog then acting against the inclined portion 79 (see Fig. 27) of the friction-plate *M'*, placed in a notch or recess at the side of and rotating with the clutch, 115 causing the said plate to be moved laterally for a sufficient distance to disengage the corner 80 from the spring 81, (see Figs. 28 and 29,) rigidly attached to the belt-wheel *N* by a bolt, 82, the belt-wheel being loose on the main 120 shaft *a*². The disengagement of the friction-plate *M'* from the belt-wheel permits the latter to run loose. The end 80 of the friction-plate is disengaged from the spring 81, while the end of the dog 75 acts upon the inclined 125 portion 79 of the friction-plate, and as soon as the dog reaches the straight portion of the said plate beyond the incline, the said plate is borne against the adjustable screw or stop 83 with sufficient force to serve the purpose of 130 a brake or stop, thus causing the rotation of the clutch-wheel and shaft *a*² to cease, and thereby stopping the operation of the stitch-forming mechanism receiving its movements

from said shaft, as in my former machine. When released from the dog 75, the friction-plate M' springs back to its first position by its own resilience, one end of said plate being 5 rigidly held in a groove or recess in the clutch-wheel. When the toe of the arm 70 is on the slide-bar 67, or the higher level of the controlling-bar, the end of the dog 75 will be out of the range of the friction-plate, and the belt-10 wheel will drive the shaft a'. The toe of arm 70 is held down against the controlling-bar by the spring 84, (see Figs. 1 and 5,) attached to a pin, 85, fastened to the said arm and to the frame a.

15 To provide for stopping and starting the stitch-forming mechanism when the toe of the arm 70 is on the high level of the controlling-bar, as is sometimes necessary, the dog 75 is slotted (see Figs. 9 and 10) to receive an eccentric pin or stud, 76^a, on the inner end of a small shaft, 76, mounted in the arm 74 and provided with thumb-projections by which it may be turned. By means of the said shaft and its eccentric-pin working in the slot in the dog 75, the latter may be moved forward, so that its end will enter the groove 77 of the clutch-wheel M to be in proper position to disengage the latter from the belt-wheel N, or the said dog may be moved backward, so as to be 25 disengaged from the said clutch-wheel, thereby permitting the latter to engage and rotate the belt-wheel.

The belt-wheel N is loose on shaft a', and has attached to one side of it the eccentric 35 55, (see Figs. 27 and 28,) that actuates the lever F, (see Figs. 1 and 5,) which moves the dog 49 to effect the feeding movement of the frame a. The belt-wheel may be rotated constantly and the frame a be kept in motion, except when 40 the dog 49 is arrested, as described, by the arresting-bar o.

When the frame a is in its forward position, to enable the material to be put into the clamp and be cut, the toe of the arm 70 rests upon 45 the lower level of the controlling-bar, and the inner end of the dog 75 is in the groove 77, and acts against the plate M' to keep it from engagement with the spring 81; but as soon as the toe of the arm 70 in the backward movement of the frame a meets the inclined front end of the slide-bar 67 the latter effects the movement of the arm 70, rock-shaft 71, and arm 74, and withdraws the dog 75 from contact with the friction-plate M', and enables the 50 latter to engage the spring 81 and start the stitch-forming devices, keeping the same in regular motion until in the return forward movement of the frame a the toe of the arm 70 drops off from the end of the high plane 68 60 of the controlling-bar.

In practical work the button-holes to be stitched differ in length, and the material employed is also of various kinds—as, for instance, thick and thin cloth or leather—and 65 different users of the machine, according to the different work to be done, frequently desire to vary the length of the stitch in the di-

rection of the length of the button-hole slit and between the commencement and completion of a button-hole, the stitch being commonly made longer along the straight sides of the slit and shorter about the eye. To accommodate for this variation automatically, the bed-plate has been provided with what is denominated a "pattern-plate," 86, (see Figs. 1 and 5,) it having two different levels, the said plate being made longitudinally adjustable by a thumb-nut, 87, placed on the threaded end 88 of the pattern-plate, the said nut being placed between two stationary ears, 89 and 90, attached to the bed-plate. The lower end of the screw 56 during the movement of the frame a will, at the proper times, pass from the lower to the higher level or part of the said plate 86 and shorten the stitch, 85 and vice versa, the time at which the said screw moves from one to the other level being determined by the adjustment of the plate 86 and the part of the button-hole at which it is desired to change the length of stitch. 90 The cloth or material having been placed between the clamps, and the latter depressed, the frame being in its forward position, the cutter-lever is operated to cut the button-hole slit. As the frame a commences to move backwardly, the button-hole slit is spread, as described, and the high part of the cam 57 passes from under the toe-piece 58, and permits the spring G^a to elevate the cutter-lever. This done, the stitching mechanism is started, as has been 100 stated, and the needle d penetrates the material at one side of the slit cut therein, and at that end of the said slit opposite the eye, and the feed movement is continued until the needle has penetrated the material completely 105 along, first, one side of the slit, then about the eye, and along the opposite side of the slit, and, as the end of the button-hole is again reached, the stitch-forming devices are stopped, 110 as has been stated; but the feed is continued 115 until stopped by the arresting-bar, leaving the frame a in its forward position, with the material unclamped and the thread slackened. The needle d, having descended through the material resting upon the throat-plate C, as 120 stated, is slightly retracted, to throw out a loop for the entrance of the point 12 of the looper 2, which enters the loop of needle-thread, and by the action of roll 4 on the cam-surface 5 of the lever A' is moved laterally, to carry the 125 loop of needle-thread out to the lower edge of the button-hole slit, where the said looper dwells, while the under needle rises through the loop of needle-thread back of the heel 13, the under needle being thrust up through the 130 said loop and through the button-hole slit and diagonally across the edge of the slit, and also across the path of movement of the needle d, the under needle reaching its high point just before the needle d, in its next descent, crosses the curved part of the under needle, 3, between its two eyes, and the needle d during its further descent enters the loop of under thread carried by the under needle. The needle d

descends through the loop of thread presented above the material by the under needle, and through the throat-plate, and a second loop of needle-thread is entered by the looper, the latter entering the said loop just after the curved needle commences its descent. The needle *d* then rises, as before described, and the under needle continues its descent, and the needle *d* completes its ascent as the under needle, 5 10 15 20 25 30 35 40 45 50 55 60 65 70 75

3, completes its descent, thus drawing up the threads to set the stitch, and, owing to the tension on the upper thread being the strongest, the under thread, carried by the under-needle, 3, is drawn about and made to cover the edge of the button-hole slit, both above and below from that point of the material penetrated by the needle *d*.

I claim—

1. In a button - hole-stitching mechanism, the combination, with a throat-plate, of a reciprocating needle - bar and its eye - pointed needle *d*, the raceway-block *A'*, the needle-carrying block, its curved under needle, 3, a co-operating looper, and means for operating said needles and looper, substantially as set forth.

2. The throat-plate, the raceway-block *A'*, inclined at one side, as described, the needle-block *B* and its attached under-thread-carrying needle, combined with the needle-bar, needle *d*, and means, substantially as described, to actuate the same, whereby the under needle is made to cross the path of movement of the upper needle diagonally, substantially as described.

3. The raceway-block *A'*, the reciprocating needle-bar *b'* and its eye-pointed needle, the needle - block *B*, and under - thread carrier, combined with the looper-lever, the attached looper-lever cam, the looper-carrier, the looper, and the lever to operate the said cam, substantially as described.

4. The raceway-block *A'*, needle-block *B*, under - thread carrier 3, looper - lever, its attached cam and lever *A'*, to move the said cam and looper-lever, and the cam-surface 5, combined with the looper and looper-carrier pivoted upon the looper-lever, and moved in one direction by the said cam-surface to cause the looper to carry the loop of thread taken from the needle *d* to the edge of the button-hole slit, to operate substantially as described.

5. The raceway-block *A'*, needle-block *B*, attached under needle, looper-lever, looper-lever cam, looper and looper-carrier pivoted upon the looper-lever, the throat-plate, lever *A'*, provided with stud to operate the looper-lever cam, the link to connect the lever *A'* and the needle-block, the needle-bar, needle *d*, gears *d'* and *g'*, and means, substantially as described, to partially rotate the needle - bar and the said race, to operate substantially as set forth.

6. The bed-plate *a'*, the movable frame *a*, means, substantially as described, to reciprocate and vibrate the same, the raceway-block *A'*, the needle-block *B*, attached under needle,

looper - lever, looper - lever cam, looper and looper-carrier pivoted upon the looper-lever, the throat-plate lever *A'*, provided with stud to operate the looper-lever cam, the link to connect the lever *A'* and the needle-block, the needle-bar, needle *d*, gears *d'* and *g'*, and means, substantially as described, to partially rotate the needle-bar and the said race, to operate substantially as set forth.

7. In a button-hole-stitching machine, the throat-plate, needle-bar, needle *d*, and means, substantially as described, to operate the needle-bar, combined with the looper 2, cut to form a throat, 14, and provided with the point 12 and heel 13, and with means to operate the said looper, whereby it is made to enter the loop of needle-thread under the throat-plate and carry the loop aside to the edge of the button-hole slit for the entrance of the under needle, substantially as set forth.

8. The bed-plate, the movable frame, means, substantially as described, to reciprocate and vibrate the same, the raceway-block *A'*, block *B*, attached under needle, looper-lever, looper-lever cam, looper and looper-carrier pivoted upon the looper-lever, the throat-plate, lever *A'*, provided with stud to operate the looper-lever cam, the link to connect the lever *A'* and block, the needle-bar, needle *d*, gears *d'* and *g'*, and means, substantially as described, to partially rotate the needle-bar and the said race, and with clamping mechanism, substantially as described, to clamp and hold the material to be stitched.

9. In a button-hole sewing-machine, the combination, with stitching mechanism to stitch the edge of a button-hole and a cam having a projection, 57, of a cutting-bed, a cutter, cutter-lever, and a toe, 58, attached to the cutter, and means, substantially as described, to adjust the said toe.

10. In a button-hole sewing-machine, a stitching-forming mechanism, the cutter-bed, the cutter-lever, its attached cutter, and the adjustable toe, combined with a cam to act upon the said toe and vibrate the cutter-lever, adjustment of the said toe compensating for the wear of the bed, substantially as described.

11. In a button-hole-stitching machine, the bed-plate, its attached clamp composed of lower members, *m m*, having surfaces *m' m'*, fingers 22, provided with the plates *m'*, links 26, and springs 28, the rock-shaft having arms 29, combined with the cam-lever 33, to operate the rock-shaft and close the clamp upon the material, substantially as described.

12. In a button-hole-stitching machine, the bed-plate, its attached clamp composed of lower members *m m*, having surfaces *m' m'*, fingers 22, provided with the plates *m'*, links 26, and springs 28, the rock-shaft having arms 29, combined with the cam-lever 33, to operate the rock-shaft and close the clamp upon the material, and with the movable frame and pivoted spreader to operate upon the studs 65 of the lower members, *m*, of the clamp, as and for the purposes set forth.

13. In a button-hole-stitching machine, the bed-plate, the cloth-clamping mechanism, the movable frame a , the stitching mechanism carried thereby, and the pivoted spreader, combined with means, substantially as described, to reciprocate and vibrate the said frame, as and for the purposes set forth.
14. The bed-plate, the cloth-clamping mechanism and the cam-lever to effect the closing of the said clamping mechanism upon the material to be stitched, the latch on the cam-lever, the trigger-lever, and the trigger to hold the trigger-lever and retain the cam-lever in position to keep the clamping mechanism closed, combined with the trigger-rest, movable frame, and lever having the inclined projection to release the trigger and trigger-lever at the completion of a button-hole and automatically effect the unclamping of the material, substantially as described.
15. The clamping mechanism for the material to be stitched, the lever to hold the said mechanism closed, the latch 37 thereon, and the thread-slacking lever, combined with intermediate mechanism, substantially as described, to release the lever which holds the clamping mechanism as the button-hole is completed and to operate the thread-slacking lever to draw the needle-thread and produce slack therein, to permit the removal of the material from the open clamp, as set forth.
16. The arm 29, the cam-lever 33, mounted on the bed-plate and chambered or cut away at 66, and the feed-arresting bar provided with the projection o^3 , combined with the cam-wheel and the dog 49, and with means to operate the said dog until the same is stopped by the feed-arresting bar, substantially as described.
17. The bed-plate, movable frame, the cam-wheel j , the dog 49, means, substantially as described, to operate the dog and rotate the said cam-wheel, and the feed-arresting bar provided with the projection o^3 to be acted upon by the dog 49, combined with the cam-lever 33, shaped to stop the forward movement of the feed-arresting bar and the vibration of the dog 49 when the cam-lever is in one position, the cam-lever being cut away, as described, to permit the feed-arresting bar to move forward, and permit the movement of the dog 49 when the said cam-lever is in its other position, substantially as set forth.
18. The bed-plate, the tension device, the clamping mechanism for the material to be stitched, the cam-lever 33 and its attached latch 37, and the thread-slackening lever d^6 , combined with the lever D and connecting-link E, substantially as and for the purpose described.
19. The bed-plate, the cam-lever, its latch 37, the trigger-lever, the trigger, its adjustable pin 38 and foot 39, and the trigger-rest, combined with the movable frame and its lever 41, provided with the inclined projection, to operate substantially as described.
20. The bed-plate, the controlling-bar p , having portions at its upper side in two planes, and the slide-bar 67 therein, combined with the frame a , rock-shaft 71, its arms 70, provided with a toe to rest upon the controlling-bar, and the arm 74, and the dog 75 in the arm 74, combined with the main shaft a^2 , clutch-wheel, its friction-plate, the belt-pulley and its spring 81, and with a spring to keep the toe of the arm 70 upon the controller-bar, substantially as described.
21. The bed-plate, the controller-bar, the washer p' , and bolt p^2 , and nut p^3 , combined with the slide r , having the projection r' , and with the movable frame a , rod or shaft E ^{4} , and spring 72, to operate substantially as described.
22. The controller-bar, rock-shaft 71, its arm 70, provided with the toe, the arm 74, the dog 75, and means to move it, substantially as described, combined with the movable frame a , main shaft a^2 , its attached clutch-wheel, friction-plate, and loose belt-pulley, substantially as described.
23. The bed-plate, movable frame a , shaft a^2 , loose belt-pulley and its attached eccentric, the cam-wheel, dog 49, and means, substantially as described, to operate the latter, and the three-armed lever F, moved by the said eccentric, and provided with the adjusting device 56, combined with the pattern-cam having different parts of its upper surface at different levels, the lever F, moving the dog 49 and actuating the cam-wheel, substantially as described.
24. The bed-plate, movable frame, lever A', lever g, eccentric link f^9 , shaft a^2 , disk f, and the link f^2 , attached thereto and provided with an eccentric, and pins f^4 and f^5 , combined with the stationary cam 45, in which is received a roller-stud, f^7 , on the pin f^6 , projecting from one side of the said slotted link, all to operate substantially as described.
25. In a button-hole sewing-machine, the combination, with the stationary frame and the controlling-bar p thereon, of the traveling frame a , carrying the stitch-forming mechanism, the arms 70 and 74, the dog 75, the shaft a^2 , the clutch-wheel M, fast thereon, the friction-plate M', provided with the incline, the belt-wheel N, loose on the said shaft, and the spring 81, attached to the belt-wheel and adapted to be engaged by the said friction-plate, whereby, when a button-hole is completed, the clutch will be automatically uncoupled from the belt-wheel and the operation of the stitch-forming mechanism thus suspended, substantially as set forth.

In testimony whereof I have signed my name to this specification in the presence of two subscribing witnesses.

JOHN REECE.
